UNITED STATES PATENT OFFICE.

STEPHEN REELE, OF HOUSTON, TEXAS.

DESIGN FOR AN AUTOMOBILE-TIRE.

53,608.

Specification for Design.

Patented July 15, 1919.

Application filed December 28, 1918. Serial No. 268,779. Term of patent 3½ years.

To all whom it may concern:

Be it known that I, STEPHEN REELE, a citizen of the United States, residing at Houston, in the county of Harris, State of Texas, have invented a new, original, and ornamental Design for Automobile-Tires, of which the following is a specification, reference being had to the accompanying drawing, forming part thereof.

Figure 1 is a perspective view showing my new design.

Fig. 2 is a plan view of a portion of the tread.

I claim:

The ornamental design for an automobile tire, as shown.

STEPHEN REELE.
